INVENTOR

UNITED STATES PATENT OFFICE

103,898

DESIGN FOR AN ATOMIZER CAP

Fernande Varlet Robinson, Richmond, Va.,

Application January 18, 1937, Serial No. 67,140

Term of patent 14 years

To all whom it may concern:

Be it known that I, Fernande Varlet Robinson, a citizen of the United States, residing at Richmond, in the State of Virginia, have invented a new, original, and ornamental Design for an Atomizer Cap, of which the following is a specification, reference being made to the accompanying drawing, forming a part thereof.

Fig. 1 is a side elevational view of an atomizer cap showing my new design;

Fig. 2 is a top plan view thereof.

I claim:—

The ornamental design for an atomizer cap, substantially as shown.

FERNANDE VARLET ROBINSON.
